ULTRA HIGH FREQUENCY CONVERSION
APPARATUSGeorge W. Fyler, Stratford, Conn., assignor to
General Electric Company, a corporation of
New York

Application November 30, 1942, Serial No. 467,286

9 Claims. (Cl. 250—20)

1

My invention relates to ultra high frequency receivers of the heterodyne type, and particularly to frequency converters and local oscillators for such receivers which possess increased signal to noise ratios.

Generally in radio communication systems the strength of the received signal is well above the level of thermal noise, or else, in other cases, external static from various sources is so high that ultimate sensitivity of the receiver is not required. However, in receiving apparatus such as that employed in radio locating or range finding apparatus of the reflected pulse or echo type, great range is desired and the signal to noise ratio of the receiver must be made as high as possible. It is obvious, for example, that if the signal to noise ratio is doubled, the effect may be the same as a four to one increase of the power of the transmitter.

Ultra high frequencies are normally employed in radio locating and range finding apparatus, and losses become important which are negligible in apparatus operated at lower frequencies. Various losses in the input circuit of the apparatus tend to decrease the signal strength, but in most cases these losses may be reduced so that they become negligible. To a greater degree the strength of the signal may be reduced by the input conductance of the electron discharge tube employed in the circuit. The input conductance of an electron discharge tube depends upon several factors, including dielectric losses in the glass envelope, resistance losses in the grid and cathode leads within the envelope, loading effect due to the transit time of electrons through the tube, and losses due to degeneration caused by the self-inductance of the cathode lead, and, in three electrode tubes, by the grid to plate capacity of the tube. The loading effects produced by degeneration in triode converters constitute a large portion of the input conductance, and it is one object of my invention to provide an improved high frequency receiving apparatus including an arrangement for reducing the input conductance of the electron discharge device by neutralizing degeneration produced both by cathode lead inductance and by grid to plate capacity.

It is another object of my invention to provide an ultra high frequency receiving apparatus including an improved arrangement for minimizing degeneration due to grid to plate capacity of the electron discharge device.

It is another object of my invention to provide an ultra high frequency receiving apparatus of the heterodyne type including an improved arrangement for minimizing degeneration loading effects which may occur at both radio frequencies and intermediate frequencies.

The input conductance of the electron discharge device employed in a converter which is

2

due to transit time loading effects decreases with increased plate voltage, and a high plate voltage is, therefore, desirable provided that adequate oscillator voltage, and adequate converter emission and safe plate dissipation are available. Under optimum conditions of operation, the amplitude of the oscillator voltage is critical and therefore it is desirable to maintain the voltage of the local oscillator output uniform throughout a substantial range of frequencies, and it is a further object of my invention to provide an improved oscillation generator for providing uniform and adequate voltage at ultra high frequencies with a minimum loading effect on the converter circuit.

The features of my invention which I believe to be novel are set forth with particularity in the appended claims. My invention itself, however, both as to its organization and method of operation, together with further objects and advantages thereof, may best be understood by reference to the following description taken in connection with the accompanying drawing in which Fig. 1 is a diagrammatic illustration of an ultra high frequency converter embodying my invention; Figs. 2 and 4 are bridge circuit diagrams, and Figs. 3 and 5 are curves illustrating the operating characteristics of the converter shown in Fig. 1; and Fig. 6 is a diagrammatic illustration of a modified form of my invention.

Briefly, the frequency conversion apparatus illustrated in the drawings comprises a receiver of the heterodyne type including a three-electrode electron discharge device connected as a converter and a second three-electrode electron discharge device connected as a local oscillator. Radio frequency signals are supplied to the converter device through a tuned grid circuit, and the oscillations produced by the local generator are also coupled to the grid of the converter. The oscillator is provided with a tuned grid circuit which is grounded, and the electron discharge device of the oscillator has its plate grounded at radio frequencies. An inductance is provided in the cathode lead of the oscillator discharge device and has a critical value at which the grid current in the oscillator is uniform over the tuning range of the grid circuit. The input conductance of the converter device, which is produced by the self-inductance of the cathode lead and by the grid to plate capacity of the device, is neutralized by a capacity bridge circuit, the grid to plate capacity and the grid to cathode capacity comprising two of the arms, and the plate to ground and cathode to ground capacities comprising the other two arms. Degeneration at the intermediate frequency of the intermediate frequency amplifier is minimized by a filter circuit including inductance and capaci-

tance in series resonance between cathode and ground at the intermediate frequency.

The conversion apparatus shown in Fig. 1 comprises a converter 10 and a local oscillator 11. The converter includes an electron discharge device 12 having a control electrode or grid 13, an anode 14, and a cathode 15. A tuned circuit comprising a line or bar conductor 16 parallel to and closely spaced from a portion of the chassis or shield 17 is connected between the grid 13 and the ground. Radio frequency signals are supplied to the tuned circuit through a concentric line including a shielding tube 18 and a conducting lead 19. The bar 16 is mounted in an adjustable conducting clamp 20 and the circuit is tuned by adjusting the position of the bar to change the length of the bar from the grid to the grounded chassis. The output circuit of the converter is connected between the anode 14 and ground, a suitable source of direct current, such as a battery 22, being provided. The output circuit includes an intermediate frequency transformer 23 and a radio frequency choke 24. The primary winding of the transformer 23 is connected to ground for alternating currents by a suitable condenser 25 to by-pass the battery 22. The load circuit is completed by a grid biasing resistance 26 and a radio frequency choke 27 connected in series between the cathode 15 and ground. A condenser 28 is connected across resistance 26 between the choke coil 27 and ground. A condenser 30 is connected in the cathode lead between the cathode 15 and ground, and a condenser 31 is connected between the anode 14 and ground for reasons to be explained below. The cathode lead and the lead connecting the anode to ground through the condenser 31 are preferably made as short as possible.

At ultra high frequencies, degenerative loading of the grid of the electron discharge device of the converter may occur due to the self-inductance of the cathode lead and also due to the grid to plate capacity in a three electrode device. This degeneration increases the input conductance and consequently reduces the effective signal potential at the grid. High input resistance is essential if maximum signal strength is to be attained at the control electrode of the converter, and it is therefore necessary to reduce or limit the degenerative loading of the grid circuit. The noise intensity may be expressed in terms of an equivalent resistance in series with the control electrode. The output signal depends upon the input resistance while the noise depends upon the sum of the input resistance and the noise resistance. High input resistance means a higher ratio of input resistance to the sum of the input resistance and the equivalent noise resistance so that the limit of sensitivity is more closely attained.

In order to minimize or prevent grid loading due to degeneration, the condensers 30 and 31 are selected to be of such sizes that they, together with the grid to cathode and grid to anode capacities of the device 12, constitute the four arms of a bridge, as indicated in Fig. 2, so that the bridge may be substantially in balance at frequencies within the range of radio frequencies to be impressed upon the grid 13. In Fig. 2 the grid to cathode capacity is indicated at 32 and the grid to anode capacity at 33. In representing the electron discharge device 12 and the capacity bridge in Fig. 2, the conventional equivalent generator elements have been employed, the plate resistance of the tube being indicated as r_p and

the equivalent generator as μ_{eg} . Although the numerals 30 and 31 have been employed in Fig. 2 to indicate the capacity between ground and the cathode and plate, respectively, it should be understood that these capacities in the bridge include all the capacity between the cathode and ground and plate and ground. For example, the cathode to ground capacity includes the capacity between the cathode 15 and its heater 36, if grounded, and, furthermore, the inductance of the cathode circuit to ground must also be taken into consideration as it may modify the effective capacity from cathode to ground. In Fig. 3 the converter output voltage is plotted against the cathode to ground capacity. The upper curve represents the signal voltage at the output and the lower curve the noise voltage at the output. As shown by these curves, the bridge may be balanced by adjusting the variable condenser 30, and the signal to noise ratio is greatly increased over the peak portion of the signal curve, the peak of the curve occurring at bridge balance. It will readily be apparent that over the peaked portion of the curve the strength of the signal in the output has been increased materially, whereas the noise remains substantially constant. The signal to noise ratio is, therefore, substantially increased.

A further extension of the frequency range of the converter may be realized by selecting the values of the condensers 30 and 31 so that they may be tuned to series resonance with the cathode and anode lead inductances respectively. Thus the bridge may be balanced by producing substantially zero impedance in two arms so that the anode and the cathode are both short-circuited through a low impedance to ground potential. Preferably the cathode and anode leads are tuned with their respective condensers to series resonance at the same frequency within R. F. operating range. The bridge circuit for this operation is indicated in Fig. 4 where the cathode and anode lead inductances are indicated at 38 and 39 respectively. In Fig. 4, since the condenser 30 and cathode lead inductance 38 are tuned to resonance at a frequency within the range of frequencies under consideration, the capacity represented by the condenser 30 in the bridge is the actual capacity of the condenser 30 and is not intended to include other capacities such as the cathode heater capacity. These other capacities are ineffective in the series resonant circuit.

From Figs. 2 and 4 it will now be apparent that a neutralizing bridge may be arranged such that at lower frequencies, substantial bridge balance will be obtained which will effectively neutralize loading of the grid due to degeneration, and at higher frequencies the degeneration may be effectively eliminated by the connection of the plate and cathode to ground through the series resonant connection.

It is also necessary to prevent degeneration at the intermediate frequency, however, the bridge circuits indicated in Figs. 2 and 4 are unbalanced for frequencies of the order of the intermediate frequency. Degeneration at intermediate frequency may be prevented by tuning the inductance 27 and condenser 28 in series resonance between the cathode and ground at the intermediate frequency. The reactance values of the inductance 27 and condenser 28 are made sufficiently low that degeneration is prevented over a wide range of frequencies in the neighborhood of the intermediate frequency.

The value of the resistor 26 is selected so that

the resulting bias on the grid 13 maintains the grid about at the cut-off voltage of the device 12. The oscillator 11 is coupled to the grid 13 through a condenser 40, and the peak voltage of the oscillator 11 is preferably about equal to the bias voltage of the grid 13. The oscillator frequency may be either above or below the signal frequency. However, it has been found that it is preferable to operate the oscillator at a frequency below the signal frequency and that the stability of the oscillator is increased thereby, and adequate excitation of the converter is assured. The explanation of the advantage to be gained in this manner lies in the fact that the signal input is capacitive at the higher oscillator frequency, and only a portion of the oscillator voltage appears on the grid 13, as determined by the capacity divider including the condenser 40 and the capacitive signal input circuit. Furthermore, the signal voltage tends to be greater at the oscillator than at the grid 13 because the oscillator circuit is inductive at the signal frequency and a partial series resonance tends to occur. If the oscillator is operated at a frequency lower than that of the signal, more oscillator voltage may be made to appear on the grid 13 than exists at the oscillator, and, also, the coupling of the signal to the oscillator is reduced. The result of operating the oscillator at a lower frequency than the signal frequency is a definite improvement in signal to noise ratio; in some cases the ratio may be doubled.

In order to decrease the input conductance due to the transit time of electrons through the discharge device 12 of the converter, it is desirable to employ a high voltage on the plate 14. However, when a high voltage is employed, it is also desirable that the oscillator voltage impressed upon the grid 13 be maintained at a definite value which is substantially uniform over the range of frequencies within which the oscillator is required to operate. In order that the oscillator voltage may be maintained at a substantially fixed level the plate or anode circuit of the oscillator is grounded at radio frequencies.

Referring again to the drawing, the oscillator 11 shown in Fig. 1 comprises an electron discharge device 42 having an anode 43, a control electrode or grid 44, and a cathode 45. Between the control electrode 44 and ground is connected a series tuned circuit including a transmission line or bar conductor 46 connected to the grid 44, and condensers 48 and 49 in parallel connected between the other end of the bar 46 and ground. The bar 46 is preferably mounted parallel to a grounded chassis or shielding plate of the oscillator and is spaced a short distance therefrom. A control electrode biasing resistance or grid leak 47 is connected between the bar 46 and ground near the end to which the condensers 48 and 49 are connected. The condenser 49 is variable and is employed to tune the resonant circuit. The effective length of the transmission line 46 is increased by the capacity of the condensers 48 and 49, the effective length being tuned to a quarter wavelength at the desired frequency so that the total voltage of the tuned circuit appears at the end of the bar 46 adjacent the grid 44, as indicated by the dotted voltage curve 41, the minimum voltage appearing at the bar adjacent its connection with the resistance 47. The condenser 48 limits the tuning range of the condenser 49 so that the condenser 49 will not have rapid tuning at the minimum end of its range. The anode 43 is connected at radio frequencies to

ground through a condenser 50. The direct current power supply, such as a battery 51, is connected to the anode 43 through a radio frequency choke coil 52. The device 42 is provided with a filament heater 53 which is supplied with current from a battery or other suitable source 54 through a radio frequency choke 55, the current returning through an inductance 56 in the cathode lead of the device 42; a by-pass condenser 57 is provided across the two leads of the heater 53 and a condenser 58 is provided to by-pass the battery 54 at radio frequencies. The grid 44 at which the full voltage of the oscillator appears is coupled to the grid 13 of the converter device 12 through the condenser 40. Since the plate 43 is grounded at radio frequencies, the voltage appearing at the grid 44 may be adjusted and maintained at a predetermined level.

It has been found that the size of the inductance coil 56 in the cathode circuit of the device 42 is critical and that by selecting the proper value of this inductance the voltage of the oscillator may be made substantially uniform at all frequencies within the tuning range. In Fig. 5 the grid current of the device 42 has been plotted against frequency for three values of the inductance 56. The two vertical lines in Fig. 5 represent the lower and upper limits of the frequency range of the oscillator; the dotted line 60 represents the grid current curve when the correct value of the inductance 56 is employed; the dotted curve 61 represents the grid current when the value of the inductance 56 is too small; and the curve 62, which is a similar curve, showing the current when the value of the inductance 56 is too large. The correct value of the inductance 56, as indicated by the curve 60, makes it possible to tune the oscillator 11 over its entire range of frequencies without any substantial change in the adequate and uniform voltage supplied to the converter. Values of the inductance either too large or too small may cause the oscillations to stop, or on the other hand, may cause the oscillator to superregenerate. In either case uniformity of operation is obviously lost.

At frequencies at the upper end of the range of the oscillator there is an increased tendency toward radiation which might produce non-uniformity of oscillation. However, this effect can be reduced until it is negligible by close spacing between the grid line 46 and the shield or chassis of the oscillator. By arranging the oscillator so that the grid line 46 is tuned in series with the condenser 49, it is possible to employ a larger condenser which is mechanically preferable and increases the stability of operation.

During the operation of the converter the oscillator is tuned solely by adjustment of the variable condenser 49. The value of the inductance 56, once selected, is fixed so that the oscillator will operate at all frequencies within its range of frequencies with the grid current following the curve 60 of Fig. 5.

A modified form of the converter embodying the invention is shown in Fig. 6. Corresponding elements have been designated by the same numerals as applied to the converter shown in Fig. 1. The tuned grid circuit comprises a wound inductance element 65 connected in parallel with a variable condenser 66 between the grid 13 and ground. An input line 67 is connected across a portion of the inductance 65, a grounded concentric shield 68 being provided about the line 67. The plate circuit of the device 12 includes 70 a resistance 69 connected between the primary 75 and the anode 43.

winding of the transformer 23, and the positive side of the battery 22, the grounded condenser 25 being connected to the junction of the primary winding and the resistance 69. The circuit for supplying the heater 36 is shown as including a battery 10 connected to the heater through radio frequency chokes 71 and 72, by-pass condensers 73 and 74 being provided across the heater 36 and the battery 10, respectively. The negative terminal of the battery is grounded. The converter of Fig. 6 includes the same bridging circuit as that of Fig. 1, and the anode 14 and cathode 15 are connected to ground by series resonant circuits at frequencies in the high frequency portion of the range of the converter in the same manner as in the converter of Fig. 1. The grid circuit is tuned by adjusting the condenser 66. The oscillator 11 may be coupled to the grid 13 through the condenser 40 in the same manner as in Fig. 1.

It will be evident that my invention provides a frequency conversion apparatus which is structurally simple and employs three electrode electron discharge devices at ultra high frequencies. By way of illustration only, and not by limitation, there are listed below values of circuit constants which have been found to be suitable for the circuit of Fig. 1 when employed in a particular superheterodyne frequency converter operating at a radio frequency of 400 megacycles and with the oscillator tuned to either 358 megacycles or 442 megacycles to provide an intermediate frequency of 42 megacycles. The devices 12 and 42 were type 955 Acorn triodes. The bars 16 and 46 were one fourth inch square brass rods approximately four inches long which had been silver plated and were spaced one eighth of an inch from the grounded partition 17.

Converter 10

Condenser 25=1000 $\mu\mu$ farads
 Condenser 28=220 $\mu\mu$ farads
 Condenser 30=3-30 $\mu\mu$ farads
 Condenser 31=2 $\mu\mu$ farads
 Choke 24=0.2 μ henry
 Choke 27=.064 μ henry

 Condenser 51=100 $\mu\mu$ farads
 Condenser 53=250 $\mu\mu$ farads
 Choke 52=resonant at 400 mc.
 Choke 55=resonant at 400 mc.
 Choke 56=.064 μ henry
 Resistance 47=8500 ohms

Preferably, the capacity 32 should be smaller than that of the condenser 30 in order that substantially all of the tuned grid circuit voltage impressed upon the grid appears between the grid and the cathode. Obviously, the bridge can be balanced with relatively large values of condensers 30 and 31. However, the condenser 31 adds capacity to the anode circuit and therefore the gain for a given bandwidth would be reduced by increasing this capacity. As a result, the signal to noise ratio would be reduced under conditions such that appreciable noise exists in first electron discharge tubes in the intermediate frequencies circuit connected to the output of the

converter. The selected value of the condenser 30 is, therefore, a compromise, it being three or four times the value of the cathode to grid capacity 32.

Although I have illustrated my invention as embodied in a superheterodyne receiver, other applications will readily be apparent to those skilled in the art. I do not, therefore, desire my invention to be limited to the particular circuit arrangement shown and described, and I intend in the appended claims to cover all modifications within the true spirit and scope of my invention.

What I claim as new and desire to secure by Letters Patent of the United States is:

1. In a high frequency receiving apparatus, an electron discharge device having an anode and a cathode and a control electrode, means for impressing on said control electrode oscillations within a predetermined range of ultra high frequencies, an output circuit connected between said anode and said cathode, a capacitor connecting said anode to ground, a capacitor connecting said cathode to ground, and a bridge circuit, the first two arms of which comprise respectively the cathode to ground capacity and the anode to ground capacity of said device, and the second two arms of which comprise respectively the cathode to control electrode capacity and the anode to control electrode capacity of said device, said bridge being in balance for a frequency within the lower portion of said range of frequencies whereby degeneration at said lower frequency is minimized, said first two arms of said bridge also including inductance and having their respective capacitors tuned in series with their respective inductances to resonance at a frequency in the upper portion of said range of frequencies whereby degeneration at said upper frequency is minimized.
2. In an ultra-high frequency energy receiving apparatus, an electron discharge device having an anode and a cathode and a control electrode, means for impressing on said control electrode voltage waves within a predetermined range of frequencies, means including a condenser for connecting said anode to ground, means including a condenser for connecting said cathode to ground, each of said connecting means including an inductance tuned in series with its respective condenser to substantial resonance within said range of frequencies whereby degeneration at frequencies within said range of frequencies is minimized, and an output circuit connected between said anode and said cathode.
3. In an ultra high frequency energy receiving apparatus, an electron discharge device having an anode and a cathode and a control electrode, means for impressing on said control electrode voltage waves within a predetermined range of frequencies, means including capacity and inductance in series for connecting said anode to ground, means including capacity and inductance in series for connecting said cathode to ground, each of said connecting means being series tuned to substantial resonance for frequencies within said range of frequencies, said two connecting means constituting two arms of a bridge, the other two arms of which comprise respectively the control electrode to anode capacity and the cathode to control electrode capacity of said device whereby degeneration at frequencies within said range of frequencies is minimized, and an output circuit connected to said anode.
4. In an ultra high frequency energy receiving apparatus, an electron discharge device having

an anode and a cathode and a control electrode, means for impressing on said control electrode voltage waves within a predetermined range of frequencies, means including a condenser for connecting said anode to ground, means including a condenser for connecting said cathode to ground, said two connecting means constituting two arms of a bridge the other two arms of which comprise respectively the control electrode to anode capacity and the cathode to control electrode capacity of said device, said bridge being balanced at a predetermined frequency within said range whereby degeneration at said frequency is minimized, and an output circuit connected to said anode.

5. In an ultra high frequency energy receiving apparatus, an electron discharge device having an anode and a cathode and a control electrode, means for impressing on said control electrode voltage waves within a predetermined range of frequencies, means including a condenser and inductance for connecting said anode to ground, means including a condenser and inductance in series for connecting said cathode to ground, said condensers constituting two arms of a bridge the other two arms of which comprise respectively the control electrode to anode capacity and the cathode to control electrode capacity of said device, said bridge being balanced at a predetermined frequency within said range whereby degeneration at said frequency is minimized, said condensers and inductances of said connecting means being respectively series tuned to resonance at a higher predetermined frequency within said range whereby said anode and said cathode are directly connected to ground at said higher frequency, and an output circuit connected to said anode and cathode.

6. In an ultra high frequency heterodyne receiver, an electron discharge device having an anode and a cathode and a control electrode, means for impressing on said control electrode signal oscillations within a predetermined range of frequencies, means for impressing on said control electrode local oscillations of a frequency different from that of the signal oscillations, an output circuit for said device including means tuned to the difference in frequency between said signal oscillations and said local oscillations, means including a condenser for connecting said anode to ground, and means including a condenser for connecting said cathode to ground, each of said connecting means including an inductance tuned in series with its respective condenser to substantial resonance within said range of frequencies whereby degeneration at frequencies within said range of frequencies is minimized.

7. In an ultra high frequency heterodyne receiver, an electron discharge device having an anode and a cathode and a control electrode, means for impressing on said control electrode signal oscillations within a predetermined range of frequencies, means for impressing on said control electrode local oscillations of a frequency different from that of the signal oscillations, an output circuit for said device including means tuned to the difference in frequency between said signal oscillations and said local oscillations, means including a condenser for connecting said cathode to ground, and means including a condenser for connecting said anode to ground, each of said connecting means including an inductance tuned to substantial resonance with its respective condenser at frequencies in the upper

portion of said range of frequencies for minimizing degeneration at said upper frequencies, said condensers constituting two arms of a bridge the other two arms of which comprise the control electrode to anode capacity and the cathode to control electrode capacity of said device, said bridge being balanced at frequencies in the lower portion of said range of frequencies whereby degeneration at said lower frequencies is minimized.

10 8. In an ultra high frequency heterodyne receiver, an electron discharge device having an anode and a cathode and a control electrode, means for impressing on said control electrode signal oscillations within a predetermined range of frequencies, means for impressing on said control electrode local oscillations of a frequency different from that of the signal oscillations, an output circuit for said device including means tuned to the difference in frequency between said signal oscillations and said local oscillations, means including a condenser for connecting said anode to ground, means including a condenser for connecting said cathode to ground, each of said connecting means including an inductance tuned in series with its respective condenser to substantial resonance within said range of frequencies, and means including a second condenser and a second inductance in series therewith and tuned at said difference frequency for connecting said cathode to ground at said difference frequency for minimizing degeneration at said difference frequency.

15 9. In an ultra high frequency heterodyne receiver, a first electron discharge device having an anode and a cathode and a control electrode, means for impressing on said control electrode signal oscillations within a predetermined range of frequencies, means including a local oscillator for impressing on said control electrode oscillations at a frequency different from that of the signal; an output circuit for said first device including means tuned to the difference in frequency between said signal oscillations and said local oscillations, means including a condenser for connecting said anode to ground, means including a condenser for connecting said cathode to ground, each of said connecting means including an inductance tuned in series with its respective condenser to substantial resonance within said range of frequencies whereby degeneration at frequencies within said range of frequencies is minimized, said local oscillator comprising a second electron discharge device having an anode and a cathode and a control electrode, means for tuning the control electrode circuit of said second device to resonance at said different frequency, means connecting the anode of said second device to ground at said different frequency, and a condenser for coupling the control electrode of said second device and the control electrode of said first device.
